UNITED STATES PATENT OFFICE.

HENRY S. FARQUHAR, OF WAYNE, PENNSYLVANIA.

CONTACT DEVICE FOR ELECTRIC TRACTION SYSTEMS.

1,176,440.

Specification of Letters Patent. Patented Mar. 21, 1916.

Application filed January 2, 1915. Serial No. 63.

To all whom it may concern:

Be it known that I, HENRY S. FARQUHAR, residing at Wayne, in the county of Delaware and State of Pennsylvania, have invented certain new and useful Improvements in Contact Devices for Electric Traction Systems, whereof the following is a specification, reference being had to the accompanying drawings.

10 My invention is intended for use in connection with so-called third rail systems, wherein a traveling collector shoe is employed to make electrical contact with the surface of an iron conductor.

15 The object of the invention is to insure efficiency of contact under the conditions experienced in these systems, when sleet, ice, snow or other foreign substances accumulate upon the contacting surfaces, the effect 20 thereof sometimes being such as to greatly impair if not wholly destroy the efficiency of the electrical contact.

Various adjunctive devices have been designed to overcome the difficulty referred to, 25 as for instance, auxiliary springs, or air cylinders with pistons; such devices being intended to supply additional mechanical pressure to the amount normally required. The organization essential to the embodiment of 30 these devices adds to the complication of the structure, and also to the weight of the apparatus as a whole. Furthermore if a high degree of mechanical pressure be employed, such devices cannot practically be used on 35 light conductors, or where the supports of the conductors are far enough apart to permit bending of the latter.

My present invention attains the desired end and avoids these difficulties by providing means, whereby, without substantially increasing the weight or complication of the mechanical devices, normally employed to insure proper contact, and without augmenting the normal mechanical strain transverse 45 to the conductor, the contact pressure between the conductor and the traveling element may be intensified whenever desired, and to the extent desired, by magnetic attraction.

50 In the accompanying drawings, I have illustrated an embodiment of the invention in its preferred form.

In said drawings, Figure I, represents a vertical sectional view through the mounting and retaining devices of a preferred 55 form of shoe, the third rail being also partly

indicated in section. Fig. II, is a horizontal section on the line II, II, of Fig. I, showing diagrammatically an electric circuit adapted for use in such an embodiment of the invention.

The third rail is indicated at 1, and is assumed to be of iron, or a compound possessing magnetic properties similar to those of iron. The shoe or traveling collector, in this 65 embodiment is a double one, comprising the two elongated contact pieces 2, and 3, of iron or low carbon steel, which are respectively provided with rearwardly projecting bolts 4, and 5, of iron, or similar magnetizable 70 material. Said bolts are adapted to be secured by means of nuts 6, and 7, in downwardly depending lugs 8, and 9, cast integral with, or attached to, the horizontal tubular rock-shaft 10. The tubular rock-shaft 10, is 75 supported upon an axial spindle 11, whose ends are mounted in depending brackets, one of which, 12, is shown in Fig. I, said brackets being hung from the under side of a portion 13, of the vehicle.

80 A rock-arm 15, is made integral with or secured to the tubular rock-shaft 10, the outer end of said arm being pivotally attached at 17, to a plunger 18, adapted to slide axially in a hollow cylindrical supporting piece 19, having a lug 20, pivoted at 21, to a portion of the bracket 12. A coiled spring 22, seated within the cavity of the supporting piece 19, tends normally to thrust the plunger 18, outward or toward the point 85 of attachment to the rock-arm 15. Hence when the parts are in the position shown in Fig. I, the pressure of the spring 22, tends to maintain the shoe members 2, and 3, in contact with the upper surface of the third rail 1. When, however, the shoe is raised from the rail by turning the tubular rock-shaft 10, upon its axis 11, the motion transmitted through the rock-arm 15, compresses the spring 22, until the dead point at the 90 pivot 17, is passed, and thereupon the normal pressure of the spring protruding the plunger 18, tends to retain the shoe in retracted or non-contacting position. While this particular method of maintaining the 95 shoes in either the contacting or retracted position has no direct bearing upon the subject matter of the present invention, it serves both to illustrate a preferred form of embodiment and to point out the reasons which 100 render the present invention desirable.

105 The shoe members 2, and 3, and their rear-

wardly projecting bolts 4, and 5, are constructed preferably of low carbon steel. In rear of the actual contacting surfaces of each shoe member, I surround its bolt with a coil 5 of insulated wire as shown at 25, and 26, the two coils being connected in series as indicated at 27. A lead 28, forms an electrical connection between the shoe member 3, and the coil 26.

- 10 From the remote terminal 29, of the other coil 25, a circuit is arranged, shown in this instance, as leading through a switch 31, varying resistance 32, and switch arm 33, to ground at 34. Said circuit is thus in shunt 15 relation to the motor circuit supplied from the third rail.

The shunt circuit thus derived and controlled by means of the variable resistance 32, energizes the two electromagnetic coils 20 25, and 26, and magnetizes their cores which, in this instance, comprise the shoe members 2, and 3, and their rearwardly projecting bolts 4, and 5. The local magnetic attraction between the shoe members and the third 25 rail tends to hold the former in close contact with the surface of the rail, thus supplementing the action due to the weight of the shoe and to the pressure of the spring 22. As the switch 31, and resistance 32, are so 30 located as to be under the control of the motorman upon the vehicle, he can apply, vary, and throw off the extra contacting pressure in accordance with the conditions presented. The additional pressure thus developed holds the shoes in forcible contact with the rail so that the foreign substances are disposed and the electrical efficiency of the contact enhanced.

In the embodiment just described, the 40 shoe is a double one, comprising two similar contacting members. This form is one which I have found in practice to be desirable. It is obvious however, that this duplication of the contacting element is not essential and that the invention lends itself to use in connection with a shoe consisting of a single such element.

In either case if it be assumed that the 50 weight of the shoe and character of the mechanical device for obtaining contact under normal circumstances, is the proper one for the conditions of a given system, in that the actual weight of the parts is at the minimum, and the mechanical structure of the 55 simplest permissible form, and that the organization is adapted to produce efficient contact under normal circumstances, the employment of my invention insures efficient contact under abnormal conditions, without 60 substantially adding to the weight of the parts, and with but trifling modifications of the structure itself.

I am aware that it is not broadly speaking new to utilize magnetic attraction as the means for obtaining normal contact between a traveling collector and a conductor, and I therefore do not broadly claim the same.

In order to conveniently indicate the essential properties of the material of which the fixed and traveling elements are comprised, I shall employ the term "magnetizable", meaning thereby that one of such elements is capable of becoming in whole or in part, an electro-magnet, and the other of acting in whole or in part as an armature 75 of said magnet.

Having thus described my invention, I claim:

1. In an electric traction system, the combination of a fixed conductor comprising 80 magnetizable material; a traveling collector comprising magnetizable material arranged in magnetically operative relation to said fixed conductor; mechanical means for causing said collector to bear against said conductor with normally sufficient pressure, independently of magnetic attraction; an electro-magnet coil upon said traveling collector; a source of electricity in circuit with said coil; and means for controlling said circuit.

2. In an electric traction system, the combination of a fixed conductor comprising magnetizable material; a traveling collector comprising magnetizable material arranged 95 in magnetically operative relation to said fixed conductor; mechanical means for causing said collector to bear against said conductor with normally sufficient pressure, independently of magnetic attraction; an electro-magnetic coil upon said traveling collector; a shunt from the main circuit of the system arranged in circuit with said coil; and means for controlling said shunt circuit.

3. In an electric traction system, the combination of a fixed conductor comprising magnetizable material; a traveling element comprising magnetizable material, arranged in magnetically operative relation to the 110 fixed conductor; mechanical means for normally holding the respective conducting surfaces in contact, independently of magnetic attraction; an electro-magnetic coil for said traveling element; an electric circuit for said coil; and means for controlling said circuit.

In testimony whereof, I have hereunto signed my name, at Philadelphia, Pennsylvania, this thirtieth day of December, 1914.

HENRY S. FARQUHAR.
